UNITED STATES PATENT OFFICE.

FRED S. CARR, OF NEWTON, MASSACHUSETTS, ASSIGNOR TO CARR FASTENER COMPANY, OF CAMBRIDGE, MASSACHUSETTS, A CORPORATION OF MAINE.

FASTENER.

1,300,576.

Specification of Letters Patent. Patented Apr. 15, 1919.

Application filed August 23, 1917. Serial No. 187,866.

To all whom it may concern:

Be it known that I, FRED S. CARR, a citizen of the United States, and a resident of Newton, county of Middlesex, Commonwealth of Massachusetts, (whose post-office address is care of Carr Fastener Company, Cambridge, Massachusetts,) have invented an Improvement in Fasteners, of which the following description, in connection with the accompanying drawings, is a specification, like characters on the drawings representing like parts.

This invention pertains to improvements in fasteners, and more particularly, though not exclusively to improvements in snap fasteners in which separation of two engaging elements can be effected by tipping movement of one of said elements in one direction only.

20 Referring to the drawings:

Figure 1 is a front elevation of a fastener constituting a preferred form of my invention;

Fig. 2 is a section on a line 2—2 of Fig. 1;

25 Fig. 3 is a rear view showing details of the socket and the preferred form of jaw mechanism therefor;

Fig. 4 is a rear view of the front of the socket prior to its attachment to the fabric, and shows a preferred form of attachment for the front plate of the socket to the intermediate plate of the socket.

Referring to the drawings, I have shown a stud 5 having a head 6 providing shoulders 35 7 and 8, preferably symmetrical as shown, and adapted to be engaged by a spring jaw 9 extending transversely of the socket above the stud.

The socket preferably comprises the front 40 plate 10 and the back plate 11 adapted to hold the spring forming the jaw 9 between them, and preferably providing an aperture in the front plate for the reception of the head 6 of the stud 5. The socket may be 45 attached to fabric 12 by a plate 13 and prongs 14, which are preferably integral with the front plate 10.

The stud 5 may be attached to fabric or other material in any suitable way.

50 The shoulder 7 of the stud is preferably abrupt so that separation of the stud and socket by rectilinear tension is impossible.

The intermediate plate 11 or the back plate 13 or both of said plates are, as shown, preferably slightly elongated so that the bottom 55 of the socket may be moved outwardly and upwardly, thereby permitting the shoulder 7 to slide out from under the spring jaw 9. Tipping of the socket relative to the stud 5 in any direction other than that above described is prevented by engagement of the stud 5 with the sides of the aperture through which it passes at the back of the socket.

The stud may be entered in the socket by rectilinear movement, the rounded head 6 of 65 the stud 5 crowding the jaw 9 upwardly. When the spring 9 enters the groove in the stud 5 the pressure of the jaw tends to keep the bottom of the stud in close engagement with the bottom of the aperture through the 70 socket.

In the manufacture of fasteners it is the usual practice to assemble the front plate, back plate and spring of the socket in the factory, and to leave the assembly of the 75 back plate with the rest of the socket until the socket is to be applied to the fabric. I have shown improved means for securing the intermediate plate 11 to the front plate 10 by imparting a slight twist to the prongs 14. 80 This provides a very strong and inexpensive means of attachment, which in no way interferes with the use of the prongs 14 for attachment of the back plate 13. I preferably twist the prongs 14 in the direction shown 85 in Fig. 4 so that the prongs more nearly aline with the threads of the fabric, thereby facilitating the passage of the prongs through the fabric and reducing to a minimum the amount of breakage or cutting of 90 the threads of the fabric.

While I have shown and described one embodiment of my invention, it is obvious that changes involving omission, alteration, substitution and reversal of parts, and even 95 changes in the mode of operation, may be made without departing from the scope of my invention, which is best defined in the following claims.

Claims:

1. A separable fastener including a casing comprising a front plate having prongs projecting rearwardly therefrom, a second plate secured to said front plate by offsets in said

100

prongs, and a third plate on the opposite side of the carrying fabric from said second plate and held in position by bent over portions of said prongs rearwardly of the first 5 named offsets therein.

2. A separable fastener having a casing comprising a front plate having prongs pro-

jecting rearwardly therefrom, and a second plate secured to said front plate by twisted portions of said prongs.

In testimony whereof, I have signed my name to this specification.

FRED S. CARR.
